UNITED STATES PATENT OFFICE.

LOUIS B. HASBROUCK, OF ELMIRA, NEW YORK, ASSIGNOR TO ECLIPSE TEXTILE SERVICES, INC., OF ELMIRA HEIGHTS, NEW YORK, A CORPORATION OF NEW YORK.

YARN CLEANER.

Application filed October 30, 1923. Serial No. 671,746.

To all whom it may concern:

Be it known that I, LOUIS B. HASBROUCK, a citizen of the United States, residing at Elmira, in the county of Chemung and State 5 of New York, have invented certain new and useful Improvements in Yarn Cleaners, fully described and represented in the following specification and the accompanying drawing, forming a part of the same.

10 This invention relates to yarn cleaners for removing impurities from traveling yarns, and aims to provide a simple and effective device for detaching specks and other impurities from a traveling yarn and continuously discharging such impurities from the cleaner.

Yarn cleaners heretofore made have been provided with transverse blades having operating edges adjacent to the yarn and 20 designed to detach impurities from the yarn by a scraping action, or by a scraping and brushing action. It has been found that when such edges are set in close contact to the yarn so as to have the most effective 25 scraping action, the fibrous matter which is inevitably scraped from the yarn with the impurities tends to wind about the yarn in front of the scraping edges. This results in forming rings of fiber about the yarn 30 which increase in size until they become re-attached to the yarn, forming bunches or slubs on the yarn which detract from its usefulness.

I have discovered that this difficulty may 35 be altogether eliminated by placing a smooth surface opposite the edges of the transverse blades and positioning this surface so that it is in contact with one side of the yarn while the edges of the blades contact with the other side of the yarn. The 40 distance between the edges of the blades and the smooth surface may be made less than the normal diameter of the yarn so that the blades contact firmly with the yarn and have 45 an effective scraping action; while, at the same time, the smooth surface lies in close contact with one side of the yarn and thus positively prevents any fiber which may be loosened from the yarn from passing around 50 the yarn to form rings and bunches. As the result, the impurities with any fiber which may be attached to them are effectively discharged from the cleaner.

The discharge of the particles from the

cleaner as well as the detaching of the particles from the yarn may be facilitated by using, opposite the smooth surface, blades which are mounted for reciprocatory movement in a direction approximately parallel to the travel of the yarn so that such reciprocation of the edges of the blades is caused by the travel of the yarn across their edges.

In order that the various features and advantages of the invention may clearly be understood, I will describe in detail a specific yarn cleaner embodying the invention in a form which I have found effective. Such a cleaner is shown in the accompanying drawings; in which:

Fig. 1 is a plan view of the cleaner; 70

Fig. 2 is a side view of the cleaner sectioned on the line 2—2 of Fig. 1;

Fig. 3 is an enlarged transverse section of the cleaner taken on the line 3—3 of Fig. 1;

Fig. 4 is a fragmentary horizontal section 75 of the line 4—4 of Fig. 3; and

Fig. 5 is a perspective view of one of the blades of the cleaner.

The yarn cleaner illustrated has a rectangular frame 10 which may be provided 80 with a bracket 11 for supporting the frame from a horizontal rod 12. The frame has a fixed side 13 and a movable or adjustable side 14. The ends 15, 16 of the frame may be made integral with the fixed side 13 of 85 the frame. A tension device 17 is secured to the front end 15 of the frame, that is, the end at which the traveling yarn enters the cleaner. The inside of the side 13 provides 90 a smooth flat vertical surface 20 and the ends 15 and 16 have recesses 21, 22 in their upper surfaces positioned to permit a yarn A, which has been passed through the tension device, to be drawn longitudinally 95 across the frame and in contact with the surface 20.

Cleaning and deflecting elements 30 are mounted on the movable side 14 of the frame, extend inwardly therefrom, and are provided with operative edges 31 lying in a 100 common vertical plane parallel to the surface 20. In order that these edges may be brought into firm contact with the yarn A which is drawn along the surface 20 regardless of the size of the particular yarn to be cleaned, the side 14 is mounted so that its distance from the fixed side 13 of the frame 105 may be nicely adjusted. The means by

which this adjustment is secured constitute a part of the present invention.

The front and rear ends 15, 16 of the frame 10 are provided at their outer ends 5 with vertical surfaces 40, 41 which are inclined at the same small angle to the fixed side 13 of the frame. The movable side 14 is provided with end portions 42, 43 which have inner surfaces 44, 45 which are inclined to the side 14 at the same angle as that at which the surfaces 40, 41 are inclined to the side 13. The side 14 is secured to the ends 15, 16 with its surfaces 44, 45 in contact with their surfaces 40, 41, by 10 means of screws 46 which pass through longitudinal slots 47 in end portions of the side 14. By loosening the screws 46 the side 14 may be adjusted endwise in either direction. When it is moved toward the front end of 15 the cleaner it is brought slightly further from the fixed side 13, and when moved rearwardly it is brought slightly nearer to the side 13. The inclination of the inclined surfaces is so slight that tightening of the 20 screws 46, after the proper adjustment has been obtained, does not cause longitudinal movement of the side 14. Furthermore, because of the fact that the inclined surfaces are all inclined at the same angle, adjustment 25 of the side 14 does not change the angle between the side 14 and the side 13. In all adjustments of the side 14, therefore, the edges 31 of the elements 30 are all at a uniform distance from the surface 20.

30 In the form shown, each cleaning and deflecting element 30 consists of a single piece of sheet metal forming a blade 32 and a resilient support 33. The outer end portion of the resilient support 33 is set in a transverse slot 34 in a movable side 14 of the frame. It is held in this slot by means of 35 a washer 35 which is forced down by a screw 36. The resilient support 33 extends straight inward from the side 14 of the frame, while the blade 32 extends transversely to the line of travel of the yarn and is inclined rearwardly from the vertical at an angle of about 35°. The operative edge 40 45 50 55 31 of the blade 32 is straight and perpendicular to the resilient support 33, and is inclined to the line of travel of the yarn by reason of the inclination of the blade. The operative edge 31 is made acute by forming a beveled surface 37 on the rear side 60 of the blade. To facilitate threading, the upper corner of the edge 31 of the blade 32 is rounded off at 38.

60 Each of the cleaning and deflecting elements 30 is free to vibrate through the bending of its resilient support 33. The bending of each resilient support occurs principally at the part of the support just inside the side 14 of the frame. Consequently 65 when the edge 31 of one of the blades 32 is struck by a particle projecting from the

yarn the blade turns outwardly substantially about the vertical axis lying at the inner end of the slot 34 in which the support 33 is mounted. In such turning, the upper end of the edge 31 of the blade moves in a curve 70 tangential to the plane of the other edges 31, while the part of the inner edge 31 adjacent to the yarn moves substantially in a curve tangential to the yarn. Since, however, each of the blades 32 is inclined to the 75 vertical axis about which it turns, the lower end of its edge 31 moves outwardly from the surface 20 to a greater extent than the upper portion of its inner edge. As a result when one of the resilient supports 33 is bent rearwardly, the operative edge 31 of the blade 32, instead of lying parallel to the surface 20, as in its normal position, diverges from the surface 20 toward its lower end.

80 A plurality of pins 50 extend inwardly 85 from the side 13 of the frame. The upper surfaces of these pins lie in the same horizontal plane as the lower ends of the recesses 21, 22 so that the pins prevent the yarn from dropping below the blades 42 when the cleaner is threaded, or in case the yarn is slackened in the course of the operation of the cleaner.

85 In using the device which has been described, the position of the side 14 is first adjusted to make the distance between the edges 31 and the surface 20 slightly less than the normal diameter of the yarn to be cleaned, so that both the edges 31 and the 90 surface 20 will be in firm contact with the 95 yarn when it is drawn through the cleaner. The edges are, however, not set close enough to the surface 20 to pinch the yarn or to exert a material drag or tension on it.

100 In the operation of the device the yarn is drawn through the cleaner in the direction of the arrow in Figs. 1 and 2 by means of a spooling, winding, or other machine not shown in the drawings. The travel of the 105 yarn across the edges of the blades sets the blades into vibration, and the edges of the blades detach specks and other impurities from the yarn by a scraping and brushing action. Since the surface 20 is in firm contact with the yarn, it positively prevents 110 any fiber removed from the yarn by the edges from winding around the yarn and becoming reattached to it. Consequently, the dirt removed from the yarn, together with all fibrous matter removed with it, is deflected downwardly by the blades and continuously discharged at the bottom of the cleaner. The slight outward turning of the 115 blades which occurs in their vibration prevents any fiber from becoming caught between the edges of the blades and the surface 20.

120 Since, owing to the presence of the surface 20, the edges of the blades may be placed in firm contact with the yarn with- 125 130

out danger of causing loose fibers to entwine about the yarn in front of the edges, the scraping action of the edges is very effective—so effective, indeed, that in some cases 5 the brushing action of the edges is not needed, and, in consequence, the supports of the blades may be made rigid instead of resilient. Thus, while the vibration of the blades possesses advantages, I have found 10 that certain types of yarn may be efficiently cleaned when rigidly mounted blades are used in combination with the surface 20. I wish it understood, therefore, that my invention in its broadest aspect includes the 15 use of blades so mounted; and, in other respects, also, is by no means limited to the specific form and arrangement of the parts of the illustrative embodiment which has been described.

20 Certain features of the device illustrated and described in this application form a part of the subject matter of my co-pending applications Serial No. 582,384, filed August 17, 1922, and Serial No. 671,745 filed Oct. 25 30, 1923.

What I claim is:

1. A yarn cleaner for removing particles from a traveling yarn, comprising a transverse blade having an operative edge at one 30 side of the yarn, means at the other side of the yarn providing a substantially flat smooth surface lying opposite said edge and extending in front of said edge by a distance as great as several times the diameter 35 of the yarn, and means for retaining said surface spaced at a distance from said edge which is less than the normal diameter of the yarn so that the surface lies in contact with the yarn and prevents fibrous matter 40 removed from the yarn by said blade from encircling the yarn.

2. A yarn cleaner for removing impurities from a traveling yarn, comprising a plurality of transverse blades having aligned 45 operative edges at one side of the yarn, a member at the other side of the yarn providing a smooth surface opposite said edges and a support for said blades retaining each blade with its edge spaced 50 from said surface by a distance slightly less than the normal diameter of the yarn.

3. A yarn cleaner for removing particles from a traveling yarn, comprising a plurality of transverse blades having aligned 55 operative edges, a common support for said blades, a member providing a smooth surface lying opposite to the edges of the blades, means for guiding the yarn between said surface and the edges of the blades, and means for adjustably varying the distance 60 between said support and said member so that the edges of the blades and said surface may be brought into contact with opposite sides of the yarn.

65 4. A yarn cleaner for removing impuri-

ties from a traveling yarn, comprising a plurality of transverse blades having aligned operative edges at one side of the yarn, a mounting for each blade permitting reciprocatory movement of its operative 70 edge in a direction approximately longitudinal of the yarn, and means providing a flat surface lying in contact with the yarn opposite the edges of said blades to prevent fibrous matter removed from the yarn by 75 the blades from encircling the yarn.

5. A yarn cleaner for removing impurities from a traveling yarn, comprising a plurality of transverse blades having aligned 80 operative edges at one side of the yarn, a mounting for each blade permitting a reciprocatory movement for its operative edge having a major component longitudinal of the yarn and a minor component transverse to the yarn, and means providing a flat surface lying in contact with the yarn opposite the edges of said blades to prevent fibrous matter removed from the yarn by the blades 85 from encircling the yarn.

6. A yarn cleaner for removing impurities from a traveling yarn, comprising means providing a smooth surface along which the yarn is drawn, a transverse blade having an operative edge spaced from said 90 surface, and a support for said blade permitting it to turn outwardly from said surface in a direction so inclined from the blade that the lower end of its operative edge is moved further from said surface 95 than the upper end of its said edge.

7. A yarn cleaner for removing particles from a traveling yarn, comprising a member providing a flat vertical surface, and a plurality of transverse blades having operative 100 edges lying in a common vertical plane parallel to and spaced from said vertical surface by a distance slightly less than the normal diameter of the yarn, and means for guiding the yarn between and in contact with said surface and said edges.

8. A yarn cleaner for removing particles from a traveling yarn, comprising a member providing a flat vertical surface along which the yarn is drawn, and a plurality of transverse blades having operative edges lying 105 in a common vertical plane parallel to said vertical surface and inclined so that the lower ends of their operative edges lie behind the upper ends of their operative edges.

9. A yarn cleaner for removing impurities from a traveling yarn, comprising a rectangular frame provided with recesses permitting the passage of the yarn along the inner surface of one of its sides, and a plurality of blades projecting inwardly from the opposite side of the frame and having edges opposite to said surface, and in contact with the yarn.

10. A yarn cleaner for removing impuri-

ties from a traveling yarn, comprising a rectangular frame provided with recesses permitting the passage of the yarn along the inner surface of one of its sides, a plurality of blades projecting inwardly from the opposite side of the frame and having edges opposite to said surface, and means for adjustably varying the distance between the sides of the frame so as to vary the distance between the edges of the blades and said surface.

11. A device for operating on a traveling yarn, comprising a frame across which the yarn is drawn in a longitudinal direction and which has side portions adjustably secured together on surfaces so inclined that relative longitudinal movement of the side portions varies the distance between them, and elements on said portions adapted to contact with opposite sides of the yarn.

12. In a device for operating on a traveling yarn, an adjustable frame across which the yarn is drawn in a longitudinal direction, comprising a fixed side member at one side of the yarn, end members extending from said side member and having outer surfaces inclined to said side member at the same angle, an adjustable side member at the other side of the yarn having end portions with inner surfaces inclined to said

adjustable side member at the aforesaid angle, and means for holding the inclined surfaces of the adjustable side member against the inclined surfaces of the end members while permitting longitudinal adjustment of the adjustable side member to vary its distance from the fixed side member.

13. In a device for operating on a traveling yarn, an adjustable frame comprising a fixed side member, end members extending from said side member, containing recesses to guide the yarn across the frame in a longitudinal direction, and having outer surfaces inclined to the fixed side member at the same angle and containing tapped holes, an adjustable side member having end portions containing longitudinal slots and provided with inner surfaces inclined to it at the aforesaid angle, and screws passing through the slots in the adjustable side member and into the holes in the end members to retain the inclined surfaces of said side member against the inclined surfaces of the end members while permitting longitudinal adjustment of said side member.

In testimony whereof I have hereunto set my hand.

LOUIS B. HASBROUCK.
